METHOD OF AND MEANS FOR PRODUCING BEVELLED EDGES ON METAL STRIP AND THE LIKE

Elmer E. Davis and Thomas F. Stevens, Newton Falls, Ohio, assignors to The Thomas Steel Company, Warren, Ohio, a corporation of Ohio

Application December 10, 1942, Serial No. 468,526

14 Claims.

(Cl. 164—60)

This invention relates, as indicated, to methods of and means for producing bevelled edges on metal strip and the like.

The production of metal strip having bevelled edges is of importance for uses such as mouldings, tubing stock, and a wide variety of strip stock used for the manufacture of stamped and formed sheet metal parts. Such bevelled and other special edges have heretofore been produced on metal strip by methods involving rolling, grinding or milling, which methods are not only costly, but are tedious and laborious as well. Edge rolling becomes impractical beyond certain limits of strip thickness, and grinding and milling become more and more difficult as the gauge of the chosen material becomes thinner.

In our copending application Serial No. 462,198, we have described a method of and means for removing burr from strip, which involves passage of the strip through rolls having shearing or cutting edges formed by the intersection of angularly related surfaces of revolution on the rolls.

We have discovered that by using rolls having the aforementioned angularly-related surfaces of revolution, and by increasing the angle, described as the angle α in said application, at which the strip enters the rolls, that we can produce accurately bevelled sheared edges on the strip, and thereby obviate the defects and disadvantages, as stated above, which characterize known methods of producing bevelled and other types of special edges on strip. We have found, moreover, that we can, in this manner, produce bevelled edges on metal strip or strip-like materials, such as rods, bars, etc., in a continuous manner and with equal facility and accuracy, irrespective of gauge thickness.

Other objects and advantages of the invention will be apparent during the course of the following description.

In the accompanying drawings, forming a part of this specification, and in which like numerals are employed to designate like parts throughout the same,

Fig. 1 is a plan view, showing a preferred method of and means for beveling the edges of metal strip;

Fig. 2 is a cross-sectional view, taken on the line 2—2 of Fig. 1;

Fig. 3 is a cross-sectional view, taken on the line 3—3 of Fig. 1;

Fig. 4 is a cross-sectional view of the bevelled strip, taken on the line 4—4 of Fig. 1;

Fig. 5 is a view similar to Fig. 2, but showing a modified form of the invention;

Fig. 6 is a plan view similar to Fig. 1, but showing in a more or less diagrammatic manner, a still further modification of the invention, and

Fig. 7 is a cross-sectional view, taken on the line 1—1 of Fig. 6.

Referring more particularly to Figs. 1 to 4 of the drawings, wherein, for the purpose of illustration, is shown a preferred embodiment of the invention, a pair of rolls 1, 1 is shown, these rolls being revolutely mounted on spindles or pins 2, which, in turn, are mounted in the clevis-like ends 3 of cylindrical roll holders 4. The roll holders 4 are mounted in and supported by sleeves 5, which have base plates 6 formed integrally therewith and mounted in slides 7, the base plates being maintained in position in the slides by means of gibs 8.

The roll holders 4 are adapted to be gripped in the sleeves 5, and for this purpose, the sleeves have integrally formed therewith a tubular guide which extends at right angles to the sleeve and the passage through which intersects the passage through the sleeve. Mounted in the guide 9 is a pair of tubular gripping members 10, the opposed inner ends of which have concave surfaces 11 adapted to be forced into gripping or wedging engagement with the outer surface of the roll holders 4. For this purpose, bolts 12 extend through the members 10, and have nuts 13 secured thereto, so that upon tightening of the nuts, the surfaces 11 of the members 10 are brought to bear upon the roll holders to hold the latter tightly gripped in the sleeves.

By mounting the base plates in the slides 7 in the manner described, they may be adjusted along the slides to vary the spacing of the opposed rolls 1 in accordance with the width of the strip to be bevelled.

It will be noted that in the foregoing arrangement, the rolls 1 are disposed in a substantially horizontal plane. In such case, the angularity between the strip and the rolls, necessary to produce beveling of the strip, is secured by causing the strip to pass beneath a guide roll 14, whose lowermost peripheral surface is in a plane below the plane of the surfaces of the rolls 1 over which the strip passes.

The guide roll 14 is mounted on a shaft 15, the ends of which are journalled in the arms of a U-shaped bracket 16, pivotally mounted, as at 17, on a base or support 18. In order to vary the angularity of the strip with respect to the rolls 1, the guide roll may be moved upwardly or downwardly, and for this purpose, a clevis bolt 19 is pivotally secured to the base 18, extends through the bracket 16, and has in threaded engagement

therewith above the bracket a nut 20. By drawing the nut downwardly, the roll 14 is lowered against the tension of the strip to increase the angularity of the strip to the rolls 1. By drawing nut 20 upwardly, the roll is elevated by the strip tension to decrease said angularity.

The aforesaid arrangement further includes means for applying a back tension to the strip to maintain the strip in a taut condition as it is pulled through the rolls. Such means includes a clamp base 21, a clamp bar 22 adjustable relatively to the latter, and strips 23 of felt or the like interposed between the clamp base and bar and between which the strip passes.

Each of the rolls 1 is provided at its peripheral surface with an annular recess 24, the recess being bounded at one side by a surface of revolution consisting of a conical wall 25, and at the other side by a surface of revolution in the form of an annular wall 26, formed by revolving a line extending from the inner edge of the surface 25 to the periphery of the roll, and at right angles to the axis of the roll, about the axis of the roll. For practical purposes, the wall 25 is at an angle of approximately 30 degrees to the wall 26, but this angle may be varied within reasonable limits.

For the purpose of beveling the edge of the strip S, the strip is passed through the rolls, as by pulling it in the direction indicated by the arrow in Fig. 1, with the upper side thereof disposed against the walls 25 of the recesses 24, and the lower side thereof whose edges are to be beveled adjacent the walls 26 of these recesses. The rolls 1 are spaced from each other in such a manner that as the strip is pulled through the rolls in the manner described, the walls 25 of the recesses force the strip towards the opposite walls 26, the flat lower surface of the strip S, as seen in Fig. 2, engaging the walls 26 as the strip engages the rolls. When the angle which the lower surface of the entering strip makes with the plane of the walls 26 of the rolls is sufficiently great, there results a beveling of the strip which begins at the points 27 and continues to the points 28, the beveling being accomplished by the sharp edges formed by the intersection of the walls 26 of the recesses with the peripheral walls 29 of the rolls, the strip emerging from the rolls in the condition shown in Fig. 4, i. e., with the edges beveled as at 30.

It will be understood that the distance between the rolls must be properly adjusted to produce the desired beveling of the strip, but at the same time, to avoid concaving of the strip, which might occur if the rolls were too closely spaced. During the aforesaid beveling operation, the rolls will be rotated by the strip in the direction indicated by the arrows in Fig. 1.

It will be further understood that the degree of beveling or angle of bevel may be increased by increasing the angle which the lower surface of the strip makes with the plane of the surfaces 26 of the rolls, and that in the case described, this is accomplished by moving the guide roll 14 downwardly.

Inasmuch as the primary function of the guide roll 14 is to maintain the strip in a flat condition during the beveling operation, it is preferred, under some conditions to secure the angularity necessary for beveling the strip by tilting the rolls 1 downwardly in the direction of movement of the strip, instead of by lowering the guide roll. The arrangement of the various units of the beveling apparatus, under these conditions is shown in Fig. 5, wherein the rolls 1 are shown

with their surfaces 26 inclined downwardly toward the direction of the strip travel.

The tilting of the rolls for this purpose is accomplished by releasing the tubular gripping members 10 from engagement with the holders 4, rotating the latter to produce the desired tilt of the rolls 1, and then bringing the members 10 again in gripping engagement with the sleeves.

Under some conditions, the desired angularity may be produced in part by lowering the guide roll 14 and in part by tilting the rolls 1 downwardly in the manner described.

Moreover, it is desirable at times to bevel a strip by progressive stages, as in producing extreme bevels in heavy gauge strip. For this purpose, the units shown in Fig. 5, may be placed in tandem with the units shown in Fig. 1, and the strip thus partially beveled by means of horizontally disposed shearing rolls and then finish beveled by means of tilted shearing rolls.

Instead of producing a bevel by means of horizontally disposed rolls or rolls inclined in the direction of movement of the strip, an arrangement of rolls such as shown in Figs. 6 and 7 may be employed.

In this arrangement, the rolls are disposed with their axes inclined toward each other and in a plane transverse to the direction of movement of the strip. The degree of bevel in this case, is also determined by the degree of inclination of the rolls, the shearing action of the rolls being the same as produced by the previously described roll arrangements.

It will be seen from the foregoing that the bevel is produced in a neat and expeditious manner, and that the rotation of the rolls results in the constant presentation of new shearing edges to the strip, so that such wear of the rolls as occurs is uniformly distributed about the rolls.

In the practice of the foregoing methods, it is desired to point out that it is essential that the edges formed by the intersection of the walls 26 of the recesses 24 with the peripheral walls 29 of the rolls be constantly maintained in a sharp condition. This can be accomplished by sharpening such edges by taking a straight grinding cut off the walls 29 of the rolls. This grinding can be repeated until the width of the annular recess 24 has been decreased to a point approaching the gauge thickness of the material which is to be beveled, at which point the recess will no longer serve as a guide for the strip. At such time, the annular recess can again be produced until subsequent grindings eventually reduce the rolls to a minimum diameter, below which it would be impractical to go.

It is thus seen that we have provided methods for continuously producing accurately beveled edges on metal strips, at relatively low cost and with a minimum of equipment.

Other modes of applying the principle of our invention may be employed instead of the one explained, change being made as regards the means and the steps herein disclosed, provided those stated by any of the following claims or their equivalent be employed.

We therefore particularly point out and distinctly claim as our invention.

1. The method of beveling metal strip and the like which consists in passing the edge of the strip to be beveled through a recess formed by two surfaces inclined to each other, and causing the edge of the strip to bear with sufficient pressure against one of said surfaces to cause the edge of said surface to shear sufficient metal from

the edge of the strip to produce a beveling of said strip edge.

2. The method of beveling metal strip and the like which consists in passing the edge of the strip to be beveled through a roll having a recess in the periphery thereof, said recess being bounded by a flat wall and a wall inclined to said flat wall, and causing the edge of the strip to bear with sufficient pressure against said flat wall to cause the edge of said wall to shear sufficient metal from the edge of the strip to produce a beveling of said strip edge.

3. The method of beveling the edge of metal strip and the like which consists in forcing said edge against a revoluble shearing edge, which is revolved solely by the movement of the strip.

4. The method of beveling metal strip and the like which consists in passing the strip in a flat condition through rolls having shearing edges adjacent the periphery of the rolls, and applying back tension to said strip while passing the strip through said rolls at an angle to the planes of said shearing edges.

5. The method of beveling metal strip and the like which consists in providing a pair of revoluble rolls having shearing edges, and with the axis of the rolls inclined, and passing the strip through said rolls over said shearing edges, the rolls being inclined in the direction of movement of the strip.

6. The method of beveling opposite sides of a metal strip and the like, which consists in providing a pair of spaced rolls having shearing edges, the rolls being inclined toward each other, and passing the strip through said rolls over said shearing edges.

7. Means for beveling the edges of metal strip and the like, said means comprising a pair of spaced rolls having their axes inclined toward each other, each roll provided at its peripheral surface with an annular recess bounded at one side by a conical wall and at the other side by a wall in the form of a surface of revolution formed by revolving a line extending from the inner edge of the conical wall to the periphery of the roll, and at right angles to the axis of the roll, about the axis of the roll.

8. Means for beveling the edges of metal strip and the like, said means comprising a pair of spaced rolls inclined toward each other, each roll provided at its peripheral surface with an annular recess bounded by walls consisting of surfaces of revolution angularly disposed to each other.

9. Means for beveling the edges of metal strip and the like, said means comprising a pair of spaced rolls, each roll provided at its peripheral

surface with an annular recess bounded at one side by a conical wall and at the other side by a wall in the form of a surface of revolution formed by revolving a line extending from the inner edge of the conical wall to the periphery of the roll, and at right angles to the axis of the roll, about the axis of the roll, means for inclining said rolls, and means for maintaining said rolls in inclined position.

10. The method of beveling the edges of a strip, said method consisting in passing said edges over the intersections of shearing surfaces of undriven rolls which are so disposed as to guide and support the strip edges, and controlling such passage in such a manner as to cause said intersections to apply a shearing action against the strip, thereby removing sufficient material from said edges to produce a beveling thereof.

11. The method of beveling metal strip and the like which consists in providing a pair of revoluble rolls having shearing edges, and passing the strip in a flat condition through said rolls over said shearing edges, said strip being passed through the rolls at an inclination to the plane of said shearing edges.

12. The method of beveling metal strip and the like which consists in providing a pair of revoluble rolls having shearing edges, and passing the strip in a flat condition through said rolls over said shearing edges, the strip being bent longitudinally as it approaches the rolls so as to cause it to enter the rolls at an inclination to the plane of the shearing edges.

13. In combination, a pair of spaced rolls having edges for bevel-cutting the edges of a strip passed through the rolls, and means for inclining said rolls in the direction of movement of said strip.

14. The method of beveling metal strip which consists in providing a pair of opposed rolls having guide recesses in the periphery thereof and shearing edges adjacent said peripheries, said shearing edges defining a fixed plane, pulling said strip through said rolls under a controllable back tension, and controllably deflecting the travel of the strip from a straight line of pull so as to cause the strip edges to enter said recesses at an angle to said plane, and cause said shearing edges to bite into and shear off a portion of each edge of the strip, the degree of bevel being proportionate to said angle of deflection, and the shearing action continuing throughout the pull of said strip through the rolls.
